UNITED STATES PATENT OFFICE.

HOWARD L. CURD, OF WACO, TEXAS.

ANCHOR FOR GUY LINES.

Application filed August 1, 1925. Serial No. 47,525.

This invention relates to an improvement in anchors especially designed for anchoring the guy lines of poles such as telegraph poles or the like.

The object of the invention is to provide a device of this character which may be easily manufactured at a comparatively slight expense and which may be easily placed in position and yet is effective to 10 securely and rigidly anchor the guy line. The anchor constituting the present invention is so constituted that it will not creep even when subjected over a long period of time to the heaviest strains.

Other objects and advantages reside in certain novel features of the construction, arrangement and combination of parts which will be hereinafter more fully described and particularly pointed out in the appended 20 claims, reference being had to the accompanying drawings forming a part of this specification, and in which:—

Figure 1 is a view illustrating an anchor in use,

Figure 2 shows how the ground is excavated to apply the anchor, and

Figure 3 is a perspective view of the anchor member.

Referring to the drawings it will be seen 20 that the anchor constituting the present invention is constructed from a single piece of sheet steel and has a base plate 1, the forward end of which tapers to a point 2. The base plate 1 is horizontally disposed 25 in use and at each side it has integrally formed therewith horizontally disposed and rearwardly extending wings 3. In between the wings 3 an upwardly and rearwardly inclined body plate 4 is provided and at its 30 upper edge the body plate 4 has a rearwardly deflected lip 5 integrally formed therewith. Centrally the body plate 5 is formed with an opening 6 to permit of the attachment of a rod 7 by means of nuts 8, 40 the rod 7 being extended through the opening 6 and the nuts 8 being threaded on the rod and engageable with the opposite sides of the body plate. The guy line is designated 45 at 9 and has its lower end attached 50 to an eye 10 formed in the rod 7.

In excavating for the anchor an ordinary post hole 11 is formed and is provided at its bottom with a lateral enlargement 12.

The anchor is then set in place with the 55 base plate 1 and its wings 2 on the bottom

of the hole 11 and its body plate 4 engaged with the wall 12^a of the enlargement 12. The rod 7 is extended through an opening 13 formed in the ground, as shown in Fig. 2. After the rod has been attached to the body plate the hole is filled up and the earth tamped in position. With this arrangement 60 the body plate 4 resists the upward and forward pull. The upward pull is also resisted by the base plate 2 and wings 3. The base 65 plate 2 and wings 3 also prevent turning movement. Altogether the action is such that the anchor will not be moved even when subjected to the greatest strains over a long period of time.

The top nut 8 can be adjusted so that the eye of anchor rod 7 can be raised and lowered to different angles without changing position of anchor.

No special tool is required to set the 75 anchor in applied position. An ordinary digging bar can be placed behind the body plate as shown in dotted lines in Figure 2 and when the digging bar has been swung forward as a lever, the point 2 will be 80 forced into the undisturbed earth and a plate 4 will contact flatwise with the wall 12. The stress on the anchor will tend to move the latter against the earth and not 85 out of the earth.

I claim:—

1. An anchor including a flat horizontally disposed base plate and an upwardly and rearwardly inclined plate-like body portion having a substantial transverse extent and 90 having means adapting it for attachment with the part to be anchored, said horizontally disposed base plate being provided with spaced wings extending rearwardly beyond the base plate and rearwardly 95 beyond the extreme rear portion of the inclined body portion.

2. An anchor constructed of sheet steel and having a flat horizontally disposed base plate pointed at its forward edge and having spaced wings extending rearwardly beyond the rear edge for a substantial extent and an upwardly and rearwardly inclined plate-like body portion having a transverse extent approximately equal to the spacing 100 between the wings, said body portion having means adapting it for attachment with the part to be anchored.

HOWARD L. CURD.
